GOLF BALL WASHER

Dominick J. Juarez, 2803 Belfast Drive 46805, and Jack L. Stark, 1006 W. Wildwood Ave. 46807, both of Fort Wayne, Ind.

Filed Nov. 5, 1968, Ser. No. 14,319

Term of patent 7 years

Int. Cl. D15—06; D7—06
U.S. Cl. D49—1

FIG. 1

FIG. 2

FIG. 3

FIG. 4

FIG. 5

FIG. 6

FIG. 7

FIG. 8

FIG. 1 is a view in perspective showing the golf ball washer of the invention attached to a conventional golf bag as it is intended to be used, said bag being shown in broken lines for illustrative purposes only;

FIG. 2 is a view in perspective showing the golf ball washer of the invention in detail;

FIG. 3 is a view of the front thereof;

FIG. 4 is a view of the top thereof;

FIG. 5 is a view of one end thereof;

FIG. 6 is a view of the other end thereof;

FIG. 7 is a view of the back thereof; and

FIG. 8 is a view of the bottom thereof.

We claim:

The ornamental design for a golf ball washer, as shown and described.
